DESIGN.

—o—
H. HUNT.

CARPET.

No. 17,223.

Patented Mar. 29, 1887.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,223, dated March 29, 1887.

Application filed February 18, 1887. Serial No. 228,125. Term of patent 3½ years.

To all whom it may concern:

Be it known that I, HENRY HUNT, a subject of the Queen of Great Britain, residing in Greenville, in the State of New Jersey, have 5 invented a new and original Design for Carpets, of which the following is a specification, reference being had to the accompanying photograph, which forms a part of the same.

The invention relates to a design to be worked 10 into or upon surfaces, such as carpets or similar fabrics; and it consists in the novel configuration and grouping of figures herein specifically shown and claimed.

The accompanying photograph is a face view 15 of a carpet showing my new design.

The main feature of the design is the distribution over the face of an open-flower system, consisting of any desired flowers or grouping of flowers and leaves and stems, as shown 20 in the photograph, of similarly-shaped and

prominent groups of small geometric or other figured work, each group having a sharp and decided outline or configuration and forming a sort of triple-diamond figure, these figured groups being placed apart and irregularly 25 placed over the face of the design and apparently without reference to or connection with the parts of the flower figures, the one system of figures irregularly overlying the other, all as shown, and illustrated in the accompanying 30 photograph.

What I claim as new, and desire to secure by Letters Patent, is—

The design for carpets, consisting of the design substantially as shown and described.

HENRY HUNT.
